UNITED STATES PATENT OFFICE.

JOHN C. STURGEON, OF ERIE, PENNSYLVANIA.

MOTOR-VEHICLE DRIVING MECHANISM.

1,105,165.

Specification of Letters Patent.

Patented July 28, 1914.

Application filed October 2, 1913. Serial No. 793,015.

To all whom it may concern:

Be it known that I, JOHN C. STURGEON, a citizen of the United States, residing at Erie, in the county of Erie and State of Pennsylvania, have invented certain new and useful Improvements in Motor-Vehicle Driving Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to motor-vehicles wherein the motor operates the driving wheels of the vehicle at varying speeds and under varying loads. In starting such vehicles, it is not unusual for the operator to throw the clutch in suddenly, and thereby start the car with more or less of a jerk, causing great and unnecessary strain upon the mechanism, and in the usual operation of motor-vehicles, at ordinary speeds on level roads or pavements, a comparatively small amount of power is used, which is readily regulated by the normal manual adjustment of the mechanism; but when the vehicle is driven at high speed, on bad roads, or uphill, much more power is needed, and an added supply of explosive mixture to the motor is required, which, under such conditions, is usually supplied by the manual manipulation of additional valve controlling mechanism, requiring not only care on the part of the operator, but frequently causing considerable waste because of the excessive and unnecessary amount of mixture supplied to the motor by careless manipulation of the controlling mechanism.

The objects of my invention are to overcome these difficulties and to that end I provide a motor-vehicle, first, with a yielding connection between the motor clutch and the differential gear, which may be adjusted to be inoperative under the ordinary load exerted in the normal operation of the vehicle, but which will yield sufficiently under the stress of an increase of load, or of a sudden strain, as for example, when the clutch is suddenly closed, to prevent a jerk on the gear and wheels of the vehicle, and which will automatically return to its normal inoperative status as soon as such excess

load or strain upon it ceases; second, with mechanism connecting such yielding connection between the motor clutch and the differential gear with suitable valve mechanism for the control of explosive mixture supplied to the motor, automatically operating such valve mechanism, when the load on the motor is raised above the normal load for which the yielding connection is adjusted, to increase the supply of mixture to the motor in proportion to the increase of the load thereon, and automatically operating such valve mechanism to decrease the supply of mixture to the motor, as the load decreases, until it reaches the normal load, when the mechanism ceases to be operated; it being understood, however, that when the load upon the motor is at or below the normal, the supply of mixture to the motor is controlled in the usual manner.

The features of my invention are herein-after fully set forth and explained, and illustrated in the accompanying drawings, in which:

Figure 1, is a view in side elevation of a portion of a motor-vehicle driving-gear embodying my invention. Fig. 2, is an enlarged sectional detail of the clutch and yielding connection portion of the same. Fig. 3, is a detail showing parts thereof. Fig. 4, is a transverse section thereof on the line $\alpha-\alpha$ in Fig. 2, looking in the direction of the arrow. Fig. 5, is a detail view of a modified construction of the cam-mechanism between the spring supports.

In these drawings illustrating my invention, A, indicates a type of vehicle motor, A', indicates the motor-shaft, B, indicates a carburetor, C C', indicates clutch members mounted on the motor-shaft A', D, indicates the driven-shaft, D', indicates the transmission gear housing, E, indicates the differential gear housing, E', indicates the rear axle, and F, indicates one of the driving wheels of an ordinary motor-vehicle; all of which parts are of ordinary construction.

The clutch member C, is mounted on the motor-shaft A', and secured against rotation thereon by means of a spline a , so that it can be moved longitudinally thereon, and bring it into engagement with the clutch member C', this movement being controlled by means of the usual clutch lever, a part whereof is indicated by a , engaging a groove c' , in the hub C, thereof. To the clutch

member C', there is secured a sleeve H, having cam-shaped surfaces H', on the opposite end thereof, (as clearly shown in Fig. 3) and is secured against endwise movement on the 5 motor-shaft A', preferably by means of a collar a', on the shaft A', and an annular ring h, secured to the inner end portion of the sleeve H, and on opposite sides of the periphery of the end of the sleeve H, there 10 are longitudinal ribs h', as and for the purpose hereinafter set forth.

Mounted upon the end of the driven-shaft D, which is alined with the end of the motor-shaft A', there is a longitudinally 15 movable part I, secured against rotation on shaft D, by means of spline d, and provided with cam-surfaces I', (as clearly shown in Fig. 3) engaging with the cam-surfaces H', on the sleeve H, (as illustrated in Fig. 2) 20 so that when the part H, is rotated, it will operate to move the part I, longitudinally upon the shaft D, (as illustrated by dotted lines in Fig. 2). On the part I, there is a 25 sleeve portion I², adapted to pass over the end of the sleeve H, and the ribs h', thereon, (as illustrated in Fig. 2) and through opposite sides of the sleeve portion I², there 30 are screw studs i, adapted to engage the ribs h', on the sleeve H, (as illustrated in Fig. 4) and limit the rotation of the sleeve H, and the part I, relatively to each other, as and for the purpose herein set forth.

On the sleeve H, there is mounted a spiral spring J, having one end J', thereof secured 35 to the clutch member C', and the opposite end J², thereof secured to the part I, so that when the clutch member C', and the sleeve H, are rotated under ordinary loads, the spring J, causes the part I, to rotate in unison therewith; but when an excessive load 40 is placed upon the part I, the spring J, winds up, and in so doing operates to rotate the sleeve H, upon the part I, in which case the cam-surfaces H', and I', operate to 45 move the part I, longitudinally on the shaft D, until the parts H, and I, have rotated upon each other far enough to bring the ribs h', on the part H, into contact with the set screws i, (as illustrated by the dotted 50 lines in Fig. 4) when such rotation of the parts H, and I, upon each other ceases, and when the excess load upon the part I, is relieved, the longitudinal tension of the spring J, upon the parts H, and I, operates to 55 rotate the parts H, and I, back to their normal positions (as illustrated in Figs. 1 and 2). The tension of the spring J, can be regulated as desired by screwing back the screw studs i, so as to pass the ribs h', when the parts 60 H, and I, can be rotated upon each other until the spring J, is brought to the desired tension and then they can be screwed in again until they engage the ribs h', as before.

In the hub of the part I, there is an annular groove i', in which the end of the

lever L, operates; this lever L, being mounted upon an intermediate bearing or support l; to the opposite end of the lever L, there is pivoted a link M, which extends to and is pivoted to a lever N, which operates a valve b, in the branch outlet B², of the carbureter B, the valve b', in the other outlet branch B³, of the carbureter B, being operated by the ordinary manually actuated lever B', in the usual manner. The valve b, 75 being normally closed at loads which do not act sufficiently upon the spring J, to rotate the parts H, and I, upon each other, but when the load is sufficient to rotate the parts H, and I, upon each other against the tension of the spring J, the part I, is thereby moved longitudinally upon the shaft D. 80

In Fig. 5, I show a modified construction of the cam mechanism between the spring supporting sections H, and I. In 85 this construction, in lieu of the cams H', and I', on the ends of the sections H, and I, I make cam shaped grooves H², in the periphery of the end of the section H, which engage the ends of the screw studs i, in the section I, so that when rotated upon each other the section I, will move longitudinally upon the shaft D, the same as in the construction hereinbefore described. This movement of the section or part I, upon the 90 shaft D, moves the lever L, and the link M, so as to open the valve b, and supply additional mixture to the motor A; when, however, the load decreases to or below the normal tension of the spring J, the spring unwinds and thereby rotates the parts H and I, backward upon each other until they resume their normal positions with relation to each other, and the part I, moving longitudinally back on the shaft D, operates the lever L, to close the valve b, leaving the motor to operate under the normal supply of mixture controlled by the valve b'; thus the mixture supplied to the motor is automatically increased as the load strain increases 100 above the normal load, and decreased as the load strain decreases, until it again arrives at the normal load. 105

I have thus described convenient mechanism for utilizing my invention, but I do not confine myself to the particular form and arrangement of mechanism hereinbefore illustrated and described, as it is obvious that many changes both in form and arrangement of parts, may be made without departing from the spirit of my invention. 115

Therefore what I claim as new and desire to secure by Letters-Patent, is:—

1. The combination in a motor vehicle driving gear, of a motor-shaft, a driven shaft, a clutch on the motor-shaft, and a yielding connection between the clutch and driven shaft, substantially as set forth. 125

2. The combination in the driving-gear of a motor vehicle, of two shafts, clutch mem- 130

bers mounted on one of said shafts, and a spring supporting member on the other, and a spring connecting one of said clutch members with said spring supporting member, substantially as set forth.

3. The combination in a motor vehicle driving gear, of a motor shaft, a clutch member thereon, a driven shaft in alinement with said motor shaft, and a yielding connection between said clutch and the driven shaft, substantially as set forth.

4. The combination in a motor vehicle driving gear, of a motor shaft, a clutch thereon, a driven shaft in alinement with said motor shaft, a spring support thereon, and a spring connecting one of the clutch members with the spring support on the driven shaft, substantially as set forth.

5. The combination in a motor vehicle driving gear, of a motor shaft, a clutch thereon, a driven shaft in alinement with said motor shaft, a spring support thereon, and a helical spring connected at one end to one of said clutch members, and at the other with the spring support on said driven shaft, substantially as set forth.

6. The combination in a motor vehicle driving gear, of a motor-shaft, clutch members mounted thereon, a spring supporting member secured to one of said clutch members, a driven shaft, a spring supporting member mounted thereon, engaging cam-surfaces between said spring supporting members, and a spring, one end of which is secured to the spring support of said clutch member and the other to the spring supporting member on the driven shaft, substantially as set forth.

7. The combination in a motor vehicle driving gear, of a motor-shaft, clutch members mounted thereon, a spring supporting sleeve on one of said clutch members longitudinally non-movable on said shaft, cam-surfaces thereon, a driven shaft, a spring supporting member mounted thereon, mechanism thereon engaging the cam-surfaces on said sleeve, and a spring having one end secured to said sleeve, and its other end secured to the spring supporting member, on the driven shaft, substantially as set forth.

8. The combination in a motor vehicle driving gear, of a motor-shaft, clutch members mounted thereon, a sleeve on one of said clutch members longitudinally non-movable on said shaft, cam-surfaces on one end of said sleeve, longitudinal ribs on the periphery of the end of said sleeve, a driven shaft, a spring supporting member mounted thereon, and adapted to embrace the end of said sleeve and the ribs thereon, cam-surfaces on said spring supporting member engaging the cam-surfaces on said sleeve, a spring having one end secured to said sleeve, and the other to said spring supporting member, and removable studs in said spring supporting

member engaging the ribs on said sleeve, and limiting the rotation of said parts upon each other, substantially as set forth.

9. In a motor vehicle driving gear, the combination of a motor, valve mechanism 70 for controlling the motor, a driven shaft, a clutch on the motor shaft, a sliding collar on the driven shaft, a spring connecting one of the clutch members with the sliding collar on the driven shaft, and mechanism connecting said sliding collar with the valve mechanism controlling the motor, substantially as set forth.

10. In a motor vehicle, the combination of a motor, a carburetor valve mechanism 80 thereon, a clutch on the motor shaft, a cam mechanism connected therewith and actuated thereby, a driving shaft, a slidable sleeve thereon engaging said cam mechanism, a spring connecting said clutch and 85 said sliding sleeve, and mechanism operatively connecting said sliding sleeve with said carburetor valve mechanism, substantially as set forth.

11. The combination in a motor vehicle, of 90 a shaft, clutch members thereon, a spring support connected with one of said clutch members, a shaft adapted to be driven by said clutch shaft, a spring support slidably mounted thereon, a cam-surface on one of 95 said spring supporting members engaging the other, lever and link mechanism connecting said slidable spring support member with carburetor valve operating mechanism, substantially as set forth.

12. The combination in a motor vehicle, of 100 a motor-shaft, clutch members mounted thereon, a spring supporting member on one of said clutch members, cam-surfaces on said member, a driven shaft, a spring support 105 slidably mounted thereon, mechanism thereon engaging the cam-surfaces on the other spring supporting member, a spring connecting said spring supporting members, and lever and link mechanism connecting said slid- 110 able spring support with carburetor valve operating mechanism, substantially as set forth.

13. The combination in a motor vehicle, of 115 a motor, a carburetor therefor, clutch members mounted on the motor-shaft of said motor, a spring supporting sleeve connected with one of said clutch members, cam-surfaces on said sleeve, a shaft adapted to be driven by the motor-shaft, a spring support 120 slidably mounted thereon, mechanism thereon engaging the cam-surfaces on said sleeve, a spring connecting said sleeve with said sliding spring support, means for adjusting the tension of said spring, and lever and link 125 mechanism connecting said sliding spring support with the valve operating mechanism of said carburetor, substantially as set forth.

14. The combination in a motor vehicle, of 130 a motor, a carburetor therefor having two

outlets leading to the motor, valves in each of said outlets, clutch members on the motor-shaft, a spring supporting member connected with one of the clutch members, cam-surfaces on said spring supporting member, a shaft adapted to be driven by the motor-shaft, a spring support slidably mounted on said driver-shaft, cam-surfaces on said slideable spring support engaging the cam-surfaces on spring supporting member connected with the clutch member, a spring connecting said spring supporting members, and le-

ver and link mechanism operatively connecting said slideable spring support with valve operating mechanism controlling one of the 15 outlets of said carburetor, substantially as set forth.

In testimony whereof I affix my signature, in presence of two witnesses.

JOHN C. STURGEON.
